UNITED STATES PATENT OFFICE.

ANTONIO CERRUTI, OF SAN FRANCISCO, CALIFORNIA, ASSIGNOR OF TWO-
THIRDS TO FONTANA & CO., OF SAME PLACE.

CAN-WIPI NG MACHINE.

SPECIFICATION forming part of Letters Patent No. 556,879, dated March 24, 1896.

Application filed September 30, 1895. Serial No. 559,823. (No model.)

To all whom it may concern:

Be it known that I, ANTONIO CERRUTI, a citizen of the United States, residing in the city and county of San Francisco, State of California, have invented an Improvement in Can-Wiping Machines; and I hereby declare the following to be a full, clear, and exact description of the same.

My invention relates to the class of machinery for wiping cans that have been filled with liquids, especially with sirups; and my invention consists of the constructions and combinations of devices which I shall hereinafter fully describe and claim.

In the operation of filling cans with sirup it is the practice to tilt the cans, thereby spilling out from them the surplus sirup and then to wipe the open tops of said cans with brushes, so as to properly prepare them for sealing.

Figure 1 is a plan view of a can-wiping machine, one of the brushes being shown in section. Fig. 2 is a vertical section through one of the brushes. Fig. 3 is an end view showing the adjustable standards.

My can-wiping machine is especially adapted for use in connection with a preceding device or machine (not shown) by which the cans are tilted in order to spill out the surplus sirup. The framework A of the machine may be of any suitable construction. Within this frame are properly mounted terminal drums B, one of which is shown in Fig. 1, adapted to be driven by mechanism unnecessary herein to illustrate. Around the terminal drums passes an endless traveling carrier in the form of a belt C for advancing the cans through the machine. Above the carrier are the brushes G. These are rotated by a central shaft H having a pinion h, which engages with

pinions g upon the shafts g' of the brushes. The brushes are vertically adjustable by having the standards I, which support their bearings, vertically movable by means of elongated slots a, through which suitable bolts b pass into the main frame.

When the cans are filled with liquid they are tilted laterally, whereby the surplus liquid is spilled out of them. Thereupon they are placed upon the endless carrier C by which they are carried under the brushes G and

their tops wiped off to prepare the tops for subsequent sealing.

The practice in wiping the tops of the cans by hand is to wipe them first in one direction and then in the other about at right angles to the first direction. To effect this in my machine I have mounted the brushes G at an angle to each other, so that the first brush will wipe the top of the cans in one direction and the second in another direction, thereby thoroughly wiping them. These brushes must be kept clean and moist, and at the same time with a drying tendency. To effect these results the shafts g' of the brushes are made hollow and in one end have a communication with a pipe L, which said pipe communicates with a pipe M from a source of water and a pipe N from a source of steam, said communication being controlled by suitable cocks m and n, as shown.

The shaft g' of the brushes is perforated at g² within the hollow center g³ of the brush. This hollow center of the brush is formed of end heads g⁴, and the brushes themselves are made in sections extending between the end heads and separated from one another, so that between each section of the brush there is a free space designed by g⁵ to the interior.

Steam and water being constantly admitted through the pipe L, and the quantities regulated by the cocks m and n, enter the hollow center of the brushes through the perforations g² and pass outwardly between the peripheral openings g⁵ and thereby keep the brushes clean, the steam being for the purpose of heating the water and thus tending to dryness. With the second brush steam alone might be used or both steam and water, as may be desired.

The brushes are nearly surrounded by a cover P to prevent spraying as the said brushes revolve, the said cover being supported in position in any suitable manner. They are herein shown as being supported by the hubs of the brushes.

Having thus described my invention, what I claim as new, and desire to secure by Letters Patent, is—

1. In a can-wiping machine, the combination, of a frame having a support for the cans,

- a pair of brushes mounted in said frame and set at an angle to each other, and means for rotating the brushes in opposite directions consisting of a shaft mounted in the frame 5 and passing through the space between the brushes, a beveled pinion on said shaft and beveled pinions on the adjacent ends of the shafts of the brushes adapted to be engaged and driven by the first-named pinion.
- 10 2. A can-wiping machine consisting of a frame having a support for the cans, oppositely-revolvable brushes set at an angle to each other and consisting of end heads and intermediate - spaced brush - sections, the 15 standards I in which the brushes are mount-

ed, a shaft intermediate of the brushes, having a pinion, pinions on the shafts of the brushes engaged and driven by the first-named pinion, said brush-shafts being in the form of hollow perforated pipes, the water-pipe L with its valves, connecting with the shafts of the brushes and the steam-pipe N connecting with the water-pipe. 20

In witness whereof I have hereunto set my hand.

ANTONIO CERRUTI.
